UNITED STATES PATENT OFFICE.

ALMON D. HEATH, OF FORT WAYNE, INDIANA, ASSIGNOR TO WAYNE OIL TANK AND PUMP COMPANY, A CORPORATION OF INDIANA.

APPARATUS FOR TRANSPORTING VOLATILE LIQUIDS.

1,286,310.

Specification of Letters Patent.

Patented Dec. 3, 1918.

Application filed May 18, 1916. Serial No. 98,274.

To all whom it may concern:

Be it known that I, ALMON D. HEATH, a citizen of the United States of America, and resident of Fort Wayne, in the county 5 of Allen and State of Indiana, have invented certain new and useful Improvements in Apparatus for Transporting Volatile Liquids, of which the following is a specification.

This invention relates to improvements in 10 apparatus for transporting volatile liquid, intended especially for handling materials such as carbon bisulfid, sulfuric ether, benzene, naphtha, gasoline, etc. The object of the invention is to provide means in connection with a cask or tank for closing the opening 15 therein through which the same is charged for the purpose of shipment, and also to provide means for effecting the discharge of the contents of the cask into a conveying member that excludes atmospheric interference.

The object of the invention is accomplished by the construction illustrated in the accompanying drawings in which:—

25 Figure 1 is a transverse sectional view showing a portion of the shell of the cask, the valve for closing same and appurtenances used during transportation; and

30 Fig. 2 is a similar view with appurtenances used in discharging the contents of the cask.

Similar characters of reference indicate corresponding parts in both views and referring now to the same:

(1) is a cylindrical cask or drum of the 35 type ordinarily used for the shipment of liquid. (2) is an opening in the shell of the cask, and (3) is an internally threaded collar that is riveted to the shell about the opening. (4) is a nipple having screw 40 threaded relation with the collar, and having also a central guide (5) for the stem (6) of a valve (7) that seats upon the upper end of the nipple. A spring (8) is interposed between the guide and a washer (9) 45 on the valve-stem, the latter being retained upon the stem by a pin (10) which is inserted in the latter. The expansive force of the spring is intended to hold the valve normally in closed position so that the contents 50 of the cask will be retained therein.

The nipple (4) has an externally threaded flange (11) upon which is secured a cap (12) for closing the nipple at the outer end thereof, the cap having a central recess (13)

in its inner face that affords clearance for 55 the lower end of the valve-stem.

With the construction thus described the cask with its contents is transported without liability of displacement of the valve and consequent leakage.

60 In constructing the device it is the intention that the collar shall be closely fitted to the cask and that the nipple shall likewise be fitted in the collar, and also the valve is seated closely so that unintended outward 65 passage of fluid from within the cask through the nipple will be prevented.

As a means for removing the contents of 70 the cask, a discharge pipe (14) is provided with an external flange (15) that is engaged by a collar (16) which is threaded for connection with the nipple upon the flange (11), there being provided packing rings (17) and (18) placed respectively upon the upper and lower faces of the flange 75 (15) for forming close connections between the flange and nipple and the flange and collar when the pipe is positioned for use. At the upper end of the pipe is a cross-arm (19) having a central upwardly projecting lug 80 (20) thereon arranged in alinement with the valve-stem so that when the pipe is attached in connection with the nipple, and the collar (16) is screwed onto the nipple, the lug will contact and raise the valve-stem, thus 85 lifting the valve so that the contents of the cask will flow gravitally from the cask through the nipple and discharge pipe, the attachment of the latter to the nipple resulting in the opening of the valve as the 90 lug (20) is raised against the lower end of the valve-stem during the connection of the discharge pipe.

95 With the appliance thus disclosed volatile liquids may be hermetically sealed within the cask and transported, and may be withdrawn from the cask without atmospheric interference and conveyed therefrom to other storage points or for use as may be desired.

100 The pipe (14) when applied to the nipple as hereinbefore set forth may also be employed in charging the cask.

The idea of the invention contemplates a normally closed cask having a valve for the 105 admission and discharge of fluid; a cap for shielding the valve from interference during shipment of the cask; and a discharge mem-

ber adapted for connection with the valve outlet of the cask and for opening the valve when applied thereto. The cap for sealing the outer end of the nipple, and the discharge member are interchangeable and are to be applied accordingly as occasion requires.

What I claim is:—

10 A shipping-cask having a discharge opening therein, a nipple fitted in the opening, the upper end of which is flush with the opening, a spring-pressed valve seated upon the inner end of the nipple and having an

outwardly extending stem, a discharge pipe having a flange adapted to seat against the 15 outer end of the nipple and having also a central projecting lug adapted to bear directly against the valve-stem, and a collar adapted to engage the flange of the discharge pipe and the nipple.

20 In testimony whereof I affix my signature, in presence of two witnesses.

ALMON D. HEATH.
